BOBBY PIN DISPENSER AND SPREADER

James E. McArthur, San Francisco, Calif.

Application June 28, 1946, Serial No. 680,115

5 Claims. (Cl. 132—1.1)

1

My invention relates to an improved dispenser and spreader for bobby pins, the primary object of my invention being to provide novel and improved construction and relative arrangement of parts in such a device, whereby the bobby pins are more conveniently and easily available in spread condition for quick application to the hair so as to conserve effort and speed up the work of beauty operators and others.

Another important object of my invention is to provide a device of the character indicated above which is relatively simple in construction, being composed of a minimum of readily manufactured and easily assembled parts.

Another important object of my invention is to provide a rugged and serviceable device of the character indicated above which operates easily and is not readily subject to jamming or to becoming otherwise out of order or unserviceable.

Other important objects and advantageous features of my invention will be apparent from the following detailed description and accompanying drawings, wherein merely for purposes of disclosure herein, a specific but non-limitative embodiment of my invention is set forth.

In the drawings:

Figure 1 is an end elevation of said embodiment.

Figure 2 is a rear elevation.

Figure 3 is a vertical longitudinal section taken on the line 3—3 of Figure 1.

The device of my invention consists primarily in a base member adapted to be mounted on any convenient stationary or movable support, a slide member mounted on said base to be manually moved relatively to the base, means for supporting a plurality of bobby pins, cooperating means on said base and slide adapted to act when the slide is actuated for selecting one of said plurality of bobby pins and spreading it while moving it toward final, and holding means independent of the slide for holding the spread bobby pin in final position until it is removed in spread condition by the operator.

While the above described essential components of the device of my invention may assume different forms and relationship, reference in detail to the accompanying drawings will show a practical working form, in which the base, generally designated 5, comprises a thin metal plate or rigid sheet bent along a longitudinal line to define a plane generally rectangular foot portion 6, to the bottom of which vacuum cups 7 or other convenient means may be attached for mounting the device on a support (not shown) with one end of said plane portion 6 being bent up

5 at right angles to define a support flange 8; and an elongated generally rectangular slide support bracket 9 which leans rearwardly out of the perpendicular and away from the foot portion 6.

The material of the sheet is cut away to provide a longitudinally elongated clearance slot 10 between the portion 6 and that portion of the slide support bracket 9 which constitutes the narrower slide support 11 which projects beyond the flange 8.

As shown in Figure 1, the upper edge of the slide support 11 is curvilinearly bent rearwardly and downwardly and the lower edge thereof rearwardly and upwardly to define channels 12 and 13, respectively, over which are slidably engaged the complementarily formed channels 14 and 15, respectively, on the upper and lower edges of the slide 16, which is thereby longitudinally slidably mounted on the slide support 11 and rearwardly spaced therefrom.

The slide 16, like the base including the slide bracket 9 and slide support 11, may be a single stamping from thin metal plate or sheeting. The plane portion of the slide between its channels 14 and 15 is formed with a diagonal slot 17, declining from right to left, a smaller and tapered vertical slot 18 formed therein above the lower or left hand end of the slot 17, and a finger piece 19 cut therefrom and bent rearwardly at right angles. The right hand edge of the slide is formed with a spring anchoring hook 20 for one end of a contractile helical spring 21 having its opposite end anchored on a similar hook 22 formed on the back of the slide bracket 9, the spring being enclosed by a semi-circular cross section guard 23 secured to the back of said slide bracket.

Projecting forwardly from the lower edge of the slide support 11 alongside of the base bracket 8 is a rod 24 upon which the legs of bobby pins rest when loaded on the device and during spreading of a bobby pin 25, as indicated in dotted lines in Figure 3. A second similarly angulated rod 26 is secured to the slide support 11 to the left of rod 24 and thereabove in a position near the left hand end of said slide support, and immediately adjacent to the inner edge of an upset U-shaped part 27 which has a bobby pin retaining hook 28, on the upper part of its underside, which may, as shown, be cut out of the material of the part 27.

Immediately below the rod 26 and declining downwardly toward the right thereof is an abutment 29 against which the lower leg of a bobby pin is forced while the bobby pin is being spread.

The lower portion of the rod 26 is tubular and has a slot 30 in its left hand side, as indicated in Figure 3. An upright hook or finger 31 is formed near the left hand end of the slide 16 and is positioned within the tubular portion of the rod 26 when the slide is in normal retracted position and moves out of said tubular portion through the slot 30 to a far left hand position relative thereto, when the slide 16 is operated toward the left, against the resistance of the spring 21.

There works in the diagonal slot 17 in the slide 16 a pin 32 which is mounted on the slide by means of heads or flanges 33 and 34 engaging opposite sides of said slide. The pin 32 also works in a perpendicular slot 35, formed in the slide support 11, whose lower end is located in such position to the left of the rod 26 that, with the tip of the pin 32 at the bottom of the slot 35, where it initially and normally is, and with the eye 36 of a bobby pin circumscribed on the lower end of the rod 26 over the finger 31 therein, the tip of the pin 32 will be in a position between the legs of the bobby pin.

Thus, when the slide 16 is pulled or pushed toward the left (in Figure 3), the pin 32 will rise along the slots 17 and 35 bearing against the underside of the upper leg of the lowermost bobby pin on the rod 26, at the same time that the selector finger 31 engages the eye 36 of the bobby pin and pulls the bobby pin outwardly toward the left, with the lower leg of the bobby pin riding against the underside of the rod 26, until the upper leg of the bobby pin snaps over the retaining hook 28 toward the end of the stroke of the slide 16.

The operator may then release the slide 16 to be retracted by the spring 21 to its initial ready position, and the spread bobby pin remains spread in readily removable position, as shown in dotted lines in Figure 3, until removed by the operator. As the bobby pin was spread and moved outwardly to available position, the next pin above it on the rod 26 falls into position with its eye 36 over the selector finger 31 ready for the next operation of the slide 11.

It will be observed that due to the construction and operation of my device it may readily be operated and bobby pins withdrawn therefrom within one and the same hand, so that it is unnecessary to remove the other hand from the hair to which the bobby pins are to be applied.

What is claimed is:

1. A dispenser and spreader for bobby pins comprising a base adapted to be secured to a support, a slide reciprocably mounted on said base, spring means for retracting said slide inwardly after manual movement thereof to outward operated position, magazine means for holding a plurality of stacked bobby pins in unspread position on said base, selector means on said slide for selectively engaging the eye of the lowermost bobby pin, and spreading means comprising a spreading pin carried by said slide and an element on said base, said pin and said element being positioned between the legs of the bobby pin in the initial position of said slide, operating means worked by outward movement of said slide relative to said base for moving said pin transversely to the direction of movement of the slide away from said element with said selector means engaged with the eye of the bobby pin so as to spread one leg of the bobby pin away from the other leg thereof as the bobby pin is drawn out-

wardly as said slide moves outwardly relative to said base.

2. A dispenser and spreader for bobby pins comprising a base adapted to be secured to a support, a slide reciprocably mounted on said base, spring means for retracting said slide inwardly after manual movement thereof to outward operated position, magazine means for holding a plurality of stacked bobby pins in unspread position on said base, selector means on said slide for selectively engaging the eye of the lowermost bobby pin, and spreading means comprising a spreading pin carried by said slide and an element on said base, said pin and said element being positioned between the legs of the bobby pin in the initial position of said slide, operating means worked by outward movement of said slide relative to said base for moving said pin transversely to the direction of movement of the slide away from said element with said selector means engaged with the eye of the bobby pin so as to spread one leg of the bobby pin away from the other leg thereof as the bobby pin is drawn outwardly as said slide moves outwardly relative to said base, and retaining means on said base engageable by a leg of the bobby pin as the bobby pin is carried outwardly and is spread while the other leg is engaged with said element whereby the spread bobby pin is maintained in spread condition on the base until manually removed by the operator.

3. A dispenser and spreader for bobby pins comprising a base adapted to be secured to a support, a slide reciprocably mounted on said base, spring means for retracting said slide inwardly after manual movement thereof to outward operated position, magazine means for holding a plurality of stacked bobby pins in unspread position on said base, selector means on said slide for selectively engaging the eye of the lowermost bobby pin, and spreading means comprising a spreading pin carried by said slide and an element on said base, said pin and said element being positioned between the legs of the bobby pin in the initial position of said slide, operating means worked by outward movement of said slide relative to said base for moving said pin transversely to the direction of movement of the slide away from said element with said selector means engaged with the eye of the bobby pin so as to spread one leg of the bobby pin away from the other leg thereof as the bobby pin is drawn outwardly as said slide moves outwardly relative to said base, said base comprising a substantially plane foot portion, a plate-like bracket portion projecting therefrom at an obtuse angle and having a portion constituting a slide support on said bracket, said slide comprising a plate having channels on its opposite edges slidably engaging the corresponding edges of said slide support.

4. A dispenser and spreader for bobby pins comprising a base adapted to be secured to a support, a slide reciprocably mounted on said base, spring means for retracting said slide inwardly after manual movement thereof to outward operated position, magazine means for holding a plurality of stacked bobby pins in unspread position on said base, selector means on said slide for selectively engaging the eye of the lowermost bobby pin, and spreading means comprising a spreading pin carried by said slide and an element on said base, said pin and said element being positioned between the legs of the bobby pin in the initial position of said slide, operating means worked by outward movement of said slide relative to said

base for moving said pin transversely to the direction of movement of the slide away from said element with said selector means engaged with the eye of the bobby pin so as to spread one leg of the bobby pin away from the other leg thereof as the bobby pin is drawn outwardly as said slide moves outwardly relative to said base, said magazine means comprising front and rear declining rods projecting forwardly from said slide support arranged for reception of the stacked bobby pins with the eyes thereof circumscribed on the front rod and the legs thereof resting upon said rear rod, the lower part of said front rod being tubular and provided with a slot in its forward side, and said selector means comprising a finger on said slide arranged to work through said slot in the tubular lower part of said forward rod as the slide is operated and to occupy a position within said hollow part in the initial position of said slide for engaging the eye of the lowermost bobby pin.

5. A dispenser and spreader for bobby pins comprising a base adapted to be secured to a support, a slide reciprocably mounted on said base, spring means for retracting said slide inwardly after

manual movement thereof to outward operated position, magazine means for holding a plurality of stacked bobby pins in unspread position on said base, selector means on said slide for selectively engaging the eye of the lowermost bobby pin, and spreading means comprising a spreading pin carried by said slide and an element on said base, said pin and said element being positioned between the legs of the bobby pin in the initial position of said slide, operating means worked by outward movement of said slide relative to said base for moving said pin transversely to the direction of movement of the slide away from said element with said selector means engaged with the eye of the bobby pin so as to spread one leg of the bobby pin away from the other leg thereof as the bobby pin is drawn outwardly as said slide moves outwardly relative to said base, said operating means comprising intersecting perpendicular and diagonal slots formed in said slide and slide support through which said spreading pin extends in sliding engagement with the sides of said slots.

JAMES E. McARTHUR.
